ATTORNEY

UNITED STATES PATENT OFFICE.

GEORGE HOPP, OF NEW YORK, N. Y.

FASTENING MEANS FOR AWNINGS.

Application filed March 13, 1925. Serial No. 15,195.

To all whom it may concern:

Be it known that I, GEORGE HOPP, a citizen of the United States, residing at New York, in the county of New York and State of New York, have invented certain new and useful Improvements in Fastening Means for Awnings, of which the following is a specification.

This invention relates to means for fastening awnings in position of use.

One of the objects of this invention is to provide a simple contrivance, whereby the attachment and detachment of the awning will be greatly facilitated.

Another object is to provide a device that will not require the use of screw bolts to be repeatedly screwed into and unscrewed from the wall to which the awning is attached, since, when using such screw bolts, the holes made in the wall quickly wear out and do not hold the bolts.

A further object is to use a construction that will permit the awning to be attached with its head rod as close to the wall as possible in order to prevent the sun rays from passing or water from dropping through the space between the awning and wall.

A still further object of this invention is to provide a device of such construction that it could be used with awnings having curved or arched head rods to fit curved windows.

With these and other objects in view, my invention consists in the combination, arrangement and construction of parts as will be hereinafter fully described and set forth in the appended claims.

In the accompanying drawing in which similar reference characters denote corresponding parts, Fig. 1 is a perspective view of an awning partly torn away to show the new device; Fig. 2, an enlarged front view of the head rod of the awning and of my new device; Fig. 3, a cross-section thereof; Figs. 4 and 5 are respectively a front view and a cross-section of a modified construction of my device.

Referring to Figs. 1-3, *a* denotes an awning of usual construction and *b* the U-shaped head rod thereof, which, as usual, is contained in a tubular pocket formed in the upper edge of the awning. The device of which, for the attachment of an awning, three or more are used, consists of a pair of members 10, each substantially S-shaped. The upper part of each S-shaped member is

formed to a circularly curved hook 11 adapted to tightly engage around the outer face of the longitudinal curved edge of the awning stiffened by the rod *b* contained in the tubular pocket thereof. The lower hook-shaped end 12 of each member is adapted to extend behind the awning with its free end directed toward the wall of the building and to serve for the suspension of a rope pulley *c*. The two members 10 of each device are connected together by a third member 13, which, in the present example, is shown to be simply tightly hooked around the upper parts 11 of the members 10, as at 13', or may be rigidly secured thereto in any other suitable manner. These members 13 are adapted to form between themselves and the head rod or upper edge of the awning a very narrow slit or opening 16. 14 denotes a screw bolt or pin adapted to be permanently but adjustably fixed in the wall of the building and which, at its free end, is formed with a head or an enlarged flattened part 15, which is adapted to freely pass through the narrow space 16 between the member 13 and the upper edge of the awning. When the bolt is so adjusted that its flattened enlargement 15 extends in longitudinal direction, the awning can be slipped over the same. On turning the bolts, so that their heads 15 will extend transversely of said slit, the awning will be locked in position and vice versa.

In the modification shown in Figs. 4 and 5, the three members 11^a, 11^a and 13^a constituting the device are all made of an integral piece.

It will be seen that the bolts or pins 14, 15 need not be removed from the building wall, when detaching the awning, as the removal of the latter can be effected by merely turning said pins into unlocking position.

By my new construction, the cost of manufacture of the device is greatly reduced.

What I claim is:—

1. The combination with an awning having a stiffened edge, of a fastening device, comprising a pair of S-shaped members, of which the upper hooked ends are adapted to embrace from the rear the upper face of said stiffened edge and the lower hooked ends are adapted to extend rearwardly and carry rope supports, a third member connecting said S-shaped members together and adapted, when said last named members are applied to the awning, to form a narrow slit between itself and said stiffened edge of the

awning and an adjustable locking means adapted to be fixed in the wall of a building and capable, when in a certain position, of engaging said third member and said 5 stiffened edge to lock said awning in position.

2. The combination with an awning having a stiffened edge, of a fastening device, comprising a pair of S-shaped members, of 10 which the upper hooked ends are adapted to embrace from the rear the upper face of said stiffened edge and the lower hooked ends are adapted to extend rearwardly and carry rope supports, a third member connecting

said S-shaped members together and adapted, when said last named members are applied to the awning, to form a narrow slit between itself and said stiffened edge of the awning and a locking means having an elongated head piece and adapted to be adjustably fixed in the wall of a building, said head piece being adapted, when in a certain position, to engage said third member and said stiffened edge to lock said awning in position. 15 20 25

In testimony whereof I affix my signature.

GEORGE HOPP.
